US00D913287S

(12) **United States Design Patent** (10) **Patent No.:** **US D913,287 S**
(45) **Date of Patent:** **** Mar. 16, 2021**

(54) **SCANNER**

(71) Applicant: **BROTHER INDUSTRIES, LTD.**,
Nagoya (JP)

(72) Inventor: **Hiromitsu Tanaka**, Nagoya (JP)

(73) Assignee: **BROTHER INDUSTRIES, LTD.**,
Nagoya (JP)

(**) Term: **15 Years**

(21) Appl. No.: **29/698,751**

(22) Filed: **Jul. 19, 2019**

(30) **Foreign Application Priority Data**

Feb. 28, 2019 (JP) 2019-004115
(51) **LOC (13) Cl.** **14-02**

(52) **U.S. Cl.**

CLAIM

The ornamental design for a scanner, as shown and described.

DESCRIPTION

FIG. 1 is a perspective view of a scanner;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof; and,
FIG. 8 is a perspective view thereof in an alternative
configuration.
The evenly spaced broken lines depict unclaimed parts of
the scanner and form no part of the claimed design.

1 Claim, 7 Drawing Sheets
